UNITED STATES PATENT OFFICE.

NANNIE M. SHOWMAN, OF NEWARK, OHIO.

COMBINED HAIR CURLER AND CRIMPER.

SPECIFICATION forming part of Letters Patent No. 369,035, dated August 30, 1887.

Application filed May 21, 1887. Serial No. 239,019. (No model.)

To all whom it may concern:

Be it known that I, NANNIE M. SHOWMAN, a citizen of the United States, residing at Newark, in the county of Licking and State of Ohio, have invented a new and useful Improvement in Combined Hair Curling and Crimping Instruments, of which the following is a specification.

My invention relates to a combined hair curling and crimping instrument; and it consists in the construction and arrangement of the parts of the same, which will be more fully hereinafter described, and pointed out in the claims.

One object of my invention is to provide a combined curling and crimping instrument which is adapted to remain closed and to receive equal heat throughout, and is applicable for use in connection with either long or short hair.

A further object of my invention is to provide a combined curling and crimping instrument which is simple and effective in its construction and operation, strong and durable, easily handled and readily operated, positive in its result, and cheaply manufactured. I attain these objects by the device illustrated in the accompanying drawings, wherein like letters of reference indicate similar parts in the several views, and in which—

Figure 1 is a perspective view of my improved device. Fig. 2 is a perspective view of the parts thereof detached. Fig. 3 is a transverse vertical sectional view on the line $x-x$ of Fig. 1. Fig. 4 is a similar view on the line $y-y$ of Fig. 1. Fig. 5 is an enlarged view of the crimping end of the tongs, showing the manner of arranging the hair thereon and the formation of crimps.

A indicates one arm or lever of the tongs, and A' the other arm thereof. As shown in Fig. 3, the arm A is formed with a boss, a , on its one side, having a stud or pin, a' , integral with the top portion thereof. In the arm A' an aperture is formed which fits over the boss a , and has a recess, a^2 , in its outer face, in which a washer, a^3 , is adapted to be inserted and placed over the stud or pin a' when the said stud or pin is headed over on the said washer, and the two parts or levers A and A' are thus pivotally secured. A projecting stud, a^4 , is formed in-

tegrally with the arm A' , adjacent to the pivotal fastening heretofore described, and to the top portion of the arm A a flat spring, a^5 , is secured, and which passes under the projecting stud or pin a^4 . The arm A is formed with a recess, a^6 , adjacent and under the end of the spring a^5 , so as to allow free play thereof when the levers are pressed apart. By this means it will be seen that the said levers A and A' , forming the tongs entire, will be continually kept closed in engagement with each other by the action of the spring a^5 . To the one end of the lever A' a circular projection is formed, said projection A^2 being arranged on the opposite side of the pivotal point of the two levers, and in like manner the arm A is provided with a semi-tubular projection, A^3 , with which the projection A^2 engages, as shown in Fig. 4. These projections A^2 and A^3 form the curling portion of the iron or tongs. At about the central portion of the arm or lever A a spur, A^7 , is integrally formed, which is adapted to be engaged by the thumb in pressing the two portions of the lever apart.

The opposite ends of each of the arms A and A' are provided with two rounded projections, A^4 A^5 , having hilt-spurs a^8 formed integral with each, and on reverse sides, which engage with apertures or recesses a^9 , approximately situated thereto. On each side of the pivotal point of the iron or tongs it will be seen that a useful device is provided. On the side of the pivotal point opposite to the curling-irons the levers A and A' are slightly curved outward, but form a space therebetween, so as to provide a space between the irons A^4 and A^5 , adapted for use in crimping.

The manner of using my device will, it is thought, be readily understood. When it is desired to use the crimping-irons, the said irons are properly heated and the hair wrapped around the same, as shown in Fig. 5. When the hair has been wrapped the entire length of the irons, it is slipped off the same and will retain the shape assumed while thereon. When it is desired to curl the hair, the curling-irons are heated, and the hair is then wrapped or coiled around the projection A^2 . When the hair has been coiled around the entire length of the projection A^2 , the projection A^3 is pressed against the same and held against

it momentarily. The two projections are then moved apart and the hair slipped off the projection A², as will be understood.

By means of this combined device it will be seen that a convenient and useful article is provided, the function of either end of which is readily brought into play when desired, and the device entire may be constructed of such size, material, and configuration as to adapt it to the intended use and application.

The novelty and utility of my device being apparent, it is unnecessary to further enlarge upon the same.

Having thus described my invention, I claim—

1. As an improved article of manufacture, the herein-described tongs or irons having a crimping attachment formed at one end and a curling attachment at the opposite end, and the means as herein set forth for uniting and retaining the parts thereof in continuous engagement, substantially as described.

2. The combination, with the levers A and A', of the boss a, formed with the lever A, having the stud or pin a', and the washer a³, adapted to rest in a recess, a², in the lever A', and to be inserted over the stud or pin a' and secure the two parts together, substantially as described.

3. The combination, with the two levers A and A', having crimping and curling attachments respectively formed at their opposite

ends and united by the pivotal joint, as set forth, of the spring a⁵ and the lug a', substantially as described.

4. The combination, with the levers A and A', having a curling attachment and crimping attachment formed in the opposite ends thereof and integral therewith, said parts being united by the pivotal joint, as hereinbefore set forth, of the spurs a⁶, adapted to engage with approximately-situated recesses a⁹, substantially as described.

5. The combination, with the levers A and A', having crimping and curling attachments respectively formed at their outer ends, of the pivotal joint constructed as herein set forth, the lug a⁴, the spring a⁵, the thumb-spur A⁷, the spurs a⁸, and the approximately-situated recesses a⁹, substantially as described.

6. The levers A A', having a crimping attachment at one end and a curling attachment at the opposite end, and the spring to keep the levers closed.

7. The levers A A', pivoted together and having one end terminating in crimping-irons and the other end terminating in curling-irons.

In testimony that I claim the foregoing as my own I have hereto affixed my signature in the presence of two witnesses.

NANNIE M. SHOWMAN.
